CLAIM

The ornamental design for a thermo cup as shown and described.

DESCRIPTION

FIG. 1 is a right-side elevation view of a thermo cup of the present invention;

FIG. 2 a left-side elevation view of the thermo cup of FIG. 1;

FIG. 3 is a front elevation view of the thermo cup of FIG. 1;

FIG. 4 is a back elevation view of the thermo cup of FIG. 1;

FIG. 5 is a top plan view of the thermo cup of FIG. 1;

FIG. 6 is a bottom plan view of the thermo cup of FIG. 1;

FIG. 7 is a top, left, perspective view of the thermo cup of FIG. 1 in a closed configuration; and,

FIG. 8 is an exploded top, left, perspective view of the thermo cup of FIG. 1 shown in an open configuration for clarity of disclosure.

The portions of the thermo cup shown in broken lines form no part of the claimed design.

1 Claim, 7 Drawing Sheets
